UNITED STATES PATENT OFFICE

2,007,173

SPRING SUSPENSION

Paul F. Barbier, Chicago, Ill.

Application September 25, 1933, Serial No. 690,793

7 Claims. (Cl. 267—19)

My invention relates to an improvement in spring suspensions. It has for one purpose to elongate the effective base, or suspension base of such a frame. I thereby reduce the pitching action of the frame and add greatly to the riding comfort. Another purpose is to increase the flexing of the springs by employing leverage action in association with the normal spring action. The effect is as if the flexibility of the springs were increased. Another purpose is to distribute a varied load weight to an intermediate portion of the frame. Thereby I extend the effective length along the frame along which the compressing action takes place. Other objects will appear from time to time in the course of the specification and claims.

I illustrate my invention more or less diagrammatically in the accompanying drawing, wherein:

Figure 1 is a side elevation;

Figure 2 is a partial side elevation of a variant form of the invention;

Figure 3 is a plan view of the structure of Figure 2;

Figure 4 is a section on the line 4—4 of Figure 2;

Figure 5 illustrates details; and

Figure 6 is a section along the line 6—6 of Figure 2.

Like parts are indicated by like symbols throughout the specification and drawing.

A generally indicates an automobile side frame member. Pivoted to its rearward end, as at A¹, is the usual supporting spring A² of semi-elliptical type.

B indicates generally the axle which may be tied to the spring as by the U-bolt B¹ and the nuts B². The opposite end of the spring A¹, instead of being shackled to the frame, is pivoted to an intermediate link C shown in section in Figure 4. It has a fork C¹ at one end which receives the eye of the spring A², through which passes the bolt C².

The linkage or leverage system which I employ may be described as follows: D indicates a link or leverage rod pivoted as at D¹ to the frame. It is provided at its opposite end with a fork D² which is pivoted co-axially with a similar fork D⁴ of an adjacent link D³ and with the earlier mentioned link C. This will be clear, for example, in Figures 2 and 4. Another link D⁵ is shown as a double link having separate side sections passing about the spring A². It is pivoted to the link D³ as at D⁶, and is rigidly secured to the member D¹⁰ as at D⁹. The securing at this point may be effected by having opposed roughened portions

D¹¹, D¹², on the members D⁵ and D¹⁰ respectively. D¹³ is any suitable securing bolt, with its lock nut D¹⁴, whereby the parts may be adjustably positioned and held rigidly against relative rotation when adjusted. The spring A² is also pivoted to the link D³ as at D⁷, by means of the member D⁸ to which the U-bolts B¹ are secured.

The structure for the opposite end of the frame is substantially identical and need not be described in further detail, the same symbols being applied to the corresponding parts in Figure 1. It will be noted, however, that whereas in Figure 1 the two links D are co-axially pivoted as at D¹ to an intermediate portion of the frame, in Figure 2, for a larger wheel base, separate pivots are shown.

In order to secure the member D¹⁰ in relation to the spring A², I provide a lower plate below the spring, shown as E. It has two apertures E¹ through which project the eye-bolts E². Each eye-bolt has a stop washer E³ and an adjusting nut E⁴ at the lower end thereof, and a spring E⁵ compressed between the washer E³ and the lower face of the plate E. In the operation of the device the plate E and the opposed portion of the member D¹⁰ clamp against the opposite side of the spring E² and may slide somewhat therealong through a very slight excursion as the spring flexes and unflexes. To a slight extent there will be a rotation of the member D¹⁰ in relation to the eye-bolt E².

It will be realized that whereas I have shown a practical and operative device, nevertheless, many changes may be made in size, shape, number and disposition of parts without departing from the spirit of my invention. I therefore wish my drawing and my description to be taken as in a broad sense illustrative or diagrammatic, rather than as limiting me to the specific structure herein described and shown.

For example, the leverage rods can be pivoted on the inside of the frame, and any suitable guide or brace employed to insure front spring alignment. It will also be understood that the drawing is not intended as a working drawing, the parts being in some of the views shown as of considerably heavier stock than would in practice be employed, this being done for ease in illustration.

It will be noted that in Figure 2 I show in detail a friction brake or spring rebound take-up means including the extension of the link D³, the link D⁵, the member D¹⁰, etc. I have omitted this from Figure 1 inasmuch as I may employ a variety of other means if I wish to obtain this effect and my leverage addition to the action of the springs is

not dependent on the employment of any such brake or take-up. On the other hand, it may under some circumstances be convenient and helpful and it is therefore illustrated.

5 It will also be understood that my device can be modified so far as is necessary in order to adapt it for any of the various types of spring suspension or drive now employed by the manufacturers of automobiles. The present showing is based on 10 its application to what is known as a Hotchkiss drive but it may with equal readiness be applied to other drives.

The use and operation of my invention are as follows:

15 I illustrate my invention as applied to what is known as a Hotchkiss drive in which the torque and twist of the rear axle is taken through the springs and a sliding universal joint absorbs the spring arc and stretch. This is in contrast to a 20 torque tube drive.

I obtain an effective increase of the spring suspension base by extending the effective length of the springs, or by separating quite substantially the points of support between the frame and the 25 opposite ends of the springs. I employ a system of links or levers in order to increase the spring flexure and the cushioning effect of the springs. Specifically, whereas one end of each spring A^2 is secured to an end of the frame, the other end is 30 linked to a system of links and levers, which system extends from an end of the frame substantially to the middle of the frame. In the specific form of Figs. 1 and 2, I employ a link D pivoted to the frame well beyond one end of the spring 35 and a link D^5 which in effect is pivoted to the frame by a common pivot of the spring, being in effect pivoted to the frame by pivot A^1 , the end portion of the spring acting as a slight extension of the link D^5 and its associate part D^{10} . The 40 links D and D^5 are secured by the intermediate link D^3 , to which the center portion of the spring A^2 , adjacent the axle B , is pivoted.

To permit movement of the parts the opposite end of the spring A^2 is also pivoted to the linkage 45 system, the link C being pivoted in relation to the end of the spring and also in relation to the intersection of the links D and D^3 . The links D and D^3 are preferably inclined to each other as shown, to prevent buckling of the system, that is to say, of 50 upward buckling at the point of intersection of the links D and D^3 .

A connection D^9 between the members D^5 and 55 D^{10} , is rigid but adjustable, thus permitting the operator or the shop to adjust the grip of the members D^{10} and E on the spring. The actual snubbing action takes place by the engagement of the bulged lower portion D^{20} of the member 60 D^{10} with the spring. This acts as a spring friction brake and controls the rebound of the frame supporting part of the spring.

In the operation of my device the frame is supported on the springs at six points in the form of Figure 1, or at eight points in the form of 65 Figure 2. The main leverage rod D remains in a generally fixed position, with a very slight oscillation, thereby snubbing the axle torque. The member D^3 is a rotating rod extending rearwardly from the main lever rod D , and actually 70 connected to the axle. D^3 alternates the torque caused by brake action, and the rod or lever D remains in a generally fixed position. One spring end is shackled, as by the link C , and the other is secured directly to the frame. Thereby the lifting action is forced to the frame supporting 75 end. As the spring flexes, the rod D^3 rotates

slightly about its pivotal connection with the rod D , but the main rod D remains in a generally fixed position, with a very slight oscillation, and the axle torque is thereby snubbed.

I claim:

1. In a spring suspension for vehicles, a semi-elliptic spring pivoted at one end in relation to the vehicle frame, a linkage between said spring and the vehicle frame including a link pivoted to the frame at a point substantially beyond the 10 opposite spring end, a link pivoted to said first mentioned link, a pivotal connection between said second link and the spring intermediate the ends of said link, a snubbing connection between one end of said link and the spring, and an additional link connection between the opposite end of the spring and said link.

2. In a spring suspension for vehicles, a vehicle frame, a semi-elliptical spring pivoted at one end in relation to said frame, a link pivoted intermediate its ends to the intermediate portion of said spring, a link connection between one end of said link and one end of said spring, a link connection between the same end of said link and the frame, and a link connection between the opposite end of said link and the spring adjacent the connection between spring and frame.

3. In a spring suspension for vehicles, a vehicle frame, a semi-elliptical spring pivoted at one end in relation to said frame, a link pivoted intermediate its ends to the intermediate portion of said spring, a link connection between one end of said link and one end of said spring, a link connection between the same end of said link and the frame, and a link connection between the opposite end of said link and the spring adjacent the connection between spring and frame, said last mentioned link including a snubbing connection adjacent the end of the spring which is pivoted in relation to the frame.

4. In a spring suspension for vehicles, a vehicle frame, semi-elliptical front and rear springs, the front of the front spring being pivoted to the front end of the frame and the rear of the rear spring being pivoted to the rear end of the frame, a linkage connection between each spring and the frame including a link pivoted to each spring, an additional link connecting said link and said spring adjacent the free end of the spring, and an additional link, one end of which is pivoted to said first mentioned link, the other end of which is pivoted to the frame.

5. In a spring suspension for vehicles, a vehicle frame, semi-elliptical front and rear springs, the front of the front spring being pivoted to the front end of the frame and the rear of the rear spring being pivoted to the rear end of the frame, a linkage connection between each spring and the frame including a link pivoted to each spring, an additional link connecting said link and said spring adjacent the free end of the spring, and an additional link, one end of which is pivoted to said first mentioned link, the other end of which is pivoted to the frame, said additional links being concentrically pivoted to the frame intermediate the springs.

6. In a spring suspension for vehicles, a vehicle frame, semi-elliptical front and rear springs, the front of the front spring being pivoted to the front end of the frame and the rear of the rear spring being pivoted to the rear end of the frame, a linkage connection between each spring and the frame including a link pivoted to each spring, an additional link connecting said link and said spring adjacent the free end of the

spring, and an additional link, one end of which is pivoted to said first mentioned link, the other end of which is pivoted to the frame, said three links being concentrically pivoted together.

5 7. In a spring suspension for vehicles, a vehicle frame, semi-elliptical front and rear springs, the front of the front spring being pivoted to the front end of the frame and the rear of the rear spring being pivoted to the rear end of the frame, 10 a linkage connection between each spring and

the frame including a link pivoted to each spring, an additional link connecting said link and said spring adjacent the free end of the spring, and an additional link, one end of which is pivoted to said first mentioned link, the other end of which is pivoted to the frame, said three links being concentrically pivoted together, said last mentioned additional links being concentrically pivoted to the frame intermediate the springs.
